CLAIM

The ornamental design for a wristband health tracker, as shown and described.

DESCRIPTION

FIG. 1 is an isometric view of a wristband health tracker looking at the top, front, and right sides.

FIG. 2 is a further isometric view of the wristband health tracker looking at the top, back, and left sides.

FIG. 3 is a further isometric view of the wristband health tracker looking at the bottom, front, and left sides.

FIG. 4 is a further isometric view of the wristband health tracker looking at the bottom, back, and left sides.

FIG. 5 is a right side view of the wristband health tracker.

FIG. 6 is a left side view of the wristband health tracker.

FIG. 7 is a top view of the wristband health tracker.

FIG. 8 is a bottom view of the wristband health tracker.

FIG. 9 is a front view of the wristband health tracker.

FIG. 10 is a back view of the wristband health tracker; and,

FIG. 11 is an isometric view of the wristband health tracker looking at the top, front, and left sides.

The broken line showing of structural features is included for the purpose of illustrating non-claimed subject matter and forms no part of the claimed design.
